DISPOSITION OF INFLAMMABLE GASES.

1,302,871.

Specification of Letters Patent.

Patented May 6, 1919.

Application filed November 10, 1917, Serial No. 201,354. Renewed October 19, 1918. Serial No. 258,911.

To all whom it may concern:

Be it known that I, ALFRED SPICE, a citizen of the United States, and residing in Jersey City, in the State of New Jersey, have invented certain new and useful Improvements in Disposition of Inflammable Gases, of which the following is a specification, reference being had to the accompanying drawing, forming a part hereof.

10 In various industries gases are generated or set free or found which, although perhaps not dangerous in small quantities, become potential sources of danger if allowed to accumulate. Thus, in mining, the mine 15 gases become exceedingly dangerous if allowed to accumulate and to form explosive mixtures with air, whereas if they can be disposed of as they are set free they cease to constitute a source of danger. So in metallurgy and other arts which involve processes of industrial chemistry gases are generated which are dangerous only if permitted to accumulate. In the use of electrical storage batteries the hydrogen developed 20 would constitute no source of danger if it could be removed as it is generated, but as is well known, if permitted to accumulate and to mix with air it forms a highly dangerous explosive mixture, so that the use of 25 storage batteries, in submarines, which may otherwise be best suited for the purpose but evolve hydrogen freely, becomes practically impossible. It has been proposed heretofore to provide means whereby the presence 30 of a gas in dangerous quantities shall be indicated so that precautions may then be taken to remove the gas; it has also been proposed to explode the mixture of a dangerous gas with air in small quantities, with 35 40 in a confined space, so that the explosion shall not be harmful. These efforts to solve the problem presented have not led to satisfactory results in practice and the plans proposed have not been adopted generally. 45 It is the object of this invention, not to prevent the development of dangerous combustible gases nor merely to indicate the presence of such gases (although their presence is actually indicated by the operation 50 of the invention), but to provide for the disposition or the elimination of the gas, which might become dangerous, as the same is formed; in accordance with the invention the gas which might become dangerous 55 is burned or combined with oxygen, but

without flame, as it is developed, provision being made whereby the gas shall be completely burned regardless of the volume in which it is evolved or generated or set free. The invention has been developed with particular reference to the safe disposition of the hydrogen generated by the storage batteries in submarine use, in which no telltale bubbles can be permitted to escape into the water, but all the gas and the products of the combustion must be retained within the hull of the submarine. It will be obvious, however, that the invention is capable of successful application under other conditions and that it is generally applicable wherever a gas is found or set free or generated which is capable of combustion or combination with the oxygen of the air. The invention will be more fully explained hereinafter with reference to the accompanying drawing, the single figure of which represents, in a diagrammatic way, a form of apparatus suitable for the practice of the invention.

In the drawing there is represented at *a* 80 an open vessel which acts as a receiver for the gases which are to be disposed of. It might be a chamber in an industrial plant or a hooded space over the storage battery, or any other form of vessel or receiver in 85 which the gases to be disposed of are gathered and from which they may be conducted to the place of combustion and into which air to sustain the combustion of the gases may be admitted freely. In the drawing 90 this receiver is shown to be open at its end *a* for the reception of the gases and of air. Communicating with the receiver *a* are a tube or duct *b* which is preferably of small capacity and always open and may be called 95 a pilot tube, and one or more additional tubes or ducts *b'*, *b''*, *b'''* and *b''''*. The number of the tubes *b'*, *b''*, etc., will be varied according to the capacity of the apparatus and each of these tubes is normally closed 100 by a valve *c'*, *c''*, etc., each of such valves being automatically controlled, as herein-after described, so that the apparatus shall respond immediately in capacity to the volume of gas received by it. All of the tubes 105 *b*, *b'*, etc., within which the combustion of the gas is carried on, as herein-after described, may discharge the products of combustion directly into the atmosphere, or preferably, as indicated in the drawing, into 110

a common discharge tube d in which may be placed a fan d' , driven by a motor d^2 at variable speed, under automatic control, as hereinafter described, for the purpose of 5 maintaining a flow of gas, or of a mixture of gas and air, through the apparatus in proportion to the delivery of gas to the apparatus.

In each of the tubes b , b' , etc., is suitably 10 disposed a resistance wire f , f' , etc., which, in operation, is maintained by an electric current at a dull red heat, whereby the mixture of gas and air, as it passes through the tube and is brought into contact with the 15 resistance wire, is heated and the combination of the gas with the oxygen of the air is effected, the products of combustion, namely, the water vapor, produced by the chemical combination of hydrogen and some of the 20 oxygen of the air, and the air, somewhat depleted of oxygen, passing through the tube d to the place of delivery. In the application of the invention to the disposition of the hydrogen gas developed by the storage batteries 25 of a submarine, the tube d may well be conducted along the shell of the hull, so as to be cooled and then made to discharge the air and water vapor within the hull of the submarine, where the air is again enriched 30 with oxygen in the usual manner.

The resistance wire f in the pilot tube b is in circuit with a battery g and is maintained by the current therefrom, continuously, at a dull red heat. The resistance wire f forms a 35 part of an ordinary Wheatstone bridge arrangement h in the other part of which is included the coil of a galvanometer, indicated generally at k , and having the usual needle m which forms a part of an electric 40 circuit or circuits as hereinafter explained. The galvanometer is provided with a segmental series of contacts m' , m^2 , etc., the function of which is to initiate the opening of the valves c' , c^2 , etc., and with another 45 segmental series of contacts n' , n^2 , etc., the function of which, in connection with the needle m is to initiate the closing of the valves c' , c^2 , etc. Simultaneously with the opening and the closing of the several valves 50 c' , c^2 , etc., the fan and motor d' , d^2 are speeded up or slowed down, as the case may be, to vary the flow of the mixture of air and gas through the apparatus, in proportion to the quantity of gas delivered to the apparatus, any substantial variation in the quantity 55 of gas delivered being compensated for by a corresponding change in the quantity of air flowing through the apparatus, so that the combustion of the mixture remains substantially the same and favorable for complete combustion of the gas.

The galvanometer needle m is connected electrically, by a wire m^5 , with a common battery m^6 , and each of the contacts m' , m^2 , etc., is connected by a wire o' , o^2 with a cor-

responding relay coil p' , p^2 , etc., each relay coil being connected by a return wire o^5 , o^6 , etc., with the common battery m^6 .

Each of the contacts n' , n^2 , etc., is connected with a relay coil r' , r^2 , etc., and each coil is connected by a wire q^5 , q^6 , etc., to the common battery m^6 and thence, by the wire m^5 , to the needle m of the galvanometer. The two relay coils $p' r'$, $p^2 r^2$, etc., of each pair act upon a pivoted switch member s' , s^2 , etc., which is connected electrically through a wire s^5 , s^6 , etc., with an included battery to a point common to two solenoids for each valve c' , c^2 . One contact t' , t^2 , etc., for the corresponding switch s' , s^2 , etc., is connected 80 by a wire t^5 , t^6 , etc., to the corresponding binding post of a resistance box t for the motor d^2 of the fan d' , and thence by a return wire t^9 , t^{10} , etc., to the corresponding resistance wire f' , f^2 , and thence to the solenoid coil v' , v^2 , etc., each coil v' , v^2 , etc., being connected to the common point and thence, by the corresponding wire s^5 , s^6 , etc., to the switch s' , s^2 , etc.

The other contact point w' , w^2 , etc., for 90 each switch s' , s^2 , etc., is connected by a corresponding wire w^5 , w^6 , etc., with the corresponding solenoid coil x' , x^2 , etc., and thence by the common connection and the corresponding wire s^5 , s^6 , etc., with the common 95 battery, to the switch s' , s^2 , etc.

It will be understood that each resistance wire f , f' , f^2 is heated by the passage of current through it to a heat (usually a dull red heat) sufficient to bring about the combustion of the inflammable gas of the mixture which passes through the corresponding tube b , b' , etc.

When the delivery of gas to the apparatus is at a minimum, such that all of the gas, together with the air admixed with it, can pass through the pilot tube b , which is always open, the wire f continues at a dull red heat sufficient to bring about the combustion of the gas in the mixture which then passes through the tube, and the needle m of the galvanometer rests upon the contact n' , all of the valves c' , c^2 being then closed. If the quantity of gas delivered to the apparatus increases above the minimum 105 the combustion thereof in the tube b will increase the temperature of the wire f and thereby increase its resistance, so that the galvanometer needle will be caused to move from its normal position of rest toward the right. When the temperature of the wire f increases sufficiently the galvanometer needle will pass over the contact m' , thereby closing the circuit through the relay p' which will immediately act to close 110 the circuit between the switch s' and the contact t' and thereby alter the resistance in the resistance box t so that the motor d^2 will be speeded up and at the same time 115 energize the solenoid coil v' , so that it will 120

open the valve c' and heat the wire f' . The effect of opening the valve c' will be to cause a larger volume of air to enter the receiver a and thus reduce the percentage of inflammable gas in the mixture then passing to the pilot tube or duct b and to the combustion tube b' . The several speeds of the fan d' are such as to maintain a definite velocity of flow of the gaseous mixture through the pilot tube or duct and the combustion tubes whether the pilot tube or duct alone is in operation or the pilot tube or duct and one or more of the combustion tubes. When the percentage of inflammable gas in the mixture is reduced by bringing into action an additional combustion tube, the temperature of the wire f in the pilot tube or duct will be lowered and, through the consequent lowering of the resistance wire, the needle will recede from the highest contact m' , etc., which it has reached, toward but not to the next lower contact of the series n' , etc. No effect will be produced as the needle moves from one contact of the series n over a higher contact of the same series, as from the contact n' and over the contact n^2 , because the valves c' , c^2 , etc., are closed at the beginning. When the valve c' opens and the resistance wire f' in the tube b' is heated by the passage of current, the greater volume of gas delivered to the apparatus together with the greater volume of air, through the speeding up of the fan or blower, will be combined with oxygen in the tubes b , b' until the proportion of inflammable gas in the mixture increases to such an extent as to bring about a further heating of the resistance wire f , when a further movement of the galvanometer needle will take place and in like manner the valve c^2 will be opened, the wire f^2 will be heated and the motor d^2 will be further speeded up. In like manner the remaining valves may be opened in succession, the resistance wires in the respective tubes heated, and the motor further speeded up so that the entire volume of gas delivered to the apparatus will be burned as it is delivered, the volume of air necessary to maintain the proper proportion of inflammable gas in the mixture being increased in like ratio. In its forward movement the galvanometer needle passes from one of the contacts of the series n' , n^2 , etc., to the corresponding contact of the series, m' , m^2 , etc., and the valves which are opened by the passage of the needle over the contacts m' , m^2 , etc., are unaffected by the passage of the needle over the contacts n' , n^2 , etc. The same is true with respect to the speed of the fan-motor and the condition of the solenoids x' , x^2 . When, however, the galvanometer needle moves backward, or from the right to the left, it passes from a contact of the series m' , m^2 to a contact of the series n' , n^2 and therefore brings about a successive closing of the valves c^4 , c^3 , etc., a successive cutting out of current from the resistance wires f^4 , f^3 , etc., and a reduction of the speed of the fan-motor. The capacity of the apparatus to dispose of the gas delivered to it therefore varies with the volume of gas delivered to it. It will be observed, that whenever the percentage of inflammable gas in the mixture delivered to the apparatus falls below a definite minimum for the tubes which are open at the time, the consequently lowered temperature and resistance of the pilot wire f will cause the galvanometer needle to move in a direction to close one of the valves, shut off current from the resistance wire of the corresponding combustion tube, and reduce the speed of the fan-motor.

The invention, as will be readily understood, is not limited in its application to the disposition of hydrogen gas from storage batteries, but is applicable to the disposition of inflammable gas derived from other sources. So far as the invention is embodied in apparatus it will also be understood that the apparatus will be varied to suit different conditions of use and that the invention, except as pointed out in the claims, is not limited to the particular apparatus shown and described herein. It will furthermore be observed that the gases are not allowed to accumulate, and are not consumed intermittently in a closed chamber, but are combined with oxygen (but without flame) continuously as they are delivered to the apparatus, while the volume of air necessary for the proper combustion of the gas is admitted freely at all times and the volume which passes through the apparatus is at all times proportioned to the volume of gas delivered to the apparatus.

I claim as my invention:

1. The method of disposing of inflammable gases which consists in causing a mixture of the gas and air to pass in contact with an electrically heated resistance wire, and causing the variations in temperature of the resistance wire produced by variations in the quality of the mixture to bring about a corresponding variation in the volume of the mixture.
2. An apparatus for the disposition of inflammable gases, the same comprising a receiver for the gases open for the free admission of air, a tube through which the mixture of air and gas flows from the receiver, an electrically heated resistance wire in said tube to bring about the combustion of the mixture, and means the operation of which is initiated by the varying resistance of the wire with variations in the temperature of the wire due to variations in the quality of the mixture, to vary the volume of flow of the mixture through the apparatus.

3. An apparatus for the disposition of inflammable gases, the same comprising a receiver for the gas open for the admission of air, a duct for the delivery of the mixture of gas and air from the receiver, an electrically heated resistance wire in said duct, a fan to create and maintain a flow of the mixture through the apparatus, and means the operation of which is initiated by the varying 5 resistance of the wire with variations in the temperature of the wire due to variations in the quality of the mixture, to vary the speed of the fan and therefore the volume of the mixture passing through the apparatus.
- 10 4. An apparatus for the disposition of inflammable gases, the same comprising a receiver for the gas open for the admission of air, a pilot duct through which the mixture is discharged from the receiver, a second duct through which the mixture may be discharged from the receiver, a valve to control the second duct, an electrically heated resistance wire in the pilot duct, an electrically heated wire in the second duct, and 15 means the operation of which is initiated by the varying resistance of the wire in the pilot duct with variations in the tempera- 20 25
- ture of the wire due to variations in the quality of the mixture to control the valve of the second duct and the passage of current through the resistance wire of the second duct. 30
5. An apparatus for the disposition of inflammable gases the same comprising a receiver for the gas open for the admission of air, a pilot duct through which the mixture is delivered from the receiver, a second duct through which the mixture may be delivered from the receiver, a valve to control the second duct, an electrically driven fan 35 to maintain the flow of the mixture through the apparatus, an electrically heated resistance wire in the pilot duct, an electrically heated resistance wire in the second duct, and means the operation of which is initiated by the varying resistance of the resistance wire in the pilot duct with variations in the quality of the mixture to control the valve of the second duct and to control the speed of the fan. 40 45

This specification signed this 5th day of November 1917.

ALFRED SPICE.
